UNITED STATES PATENT OFFICE.

EDWARD A. GUTERMANN, OF MERIDEN, CONNECTICUT, ASSIGNOR TO
MANNING, BOWMAN & COMPANY, OF MERIDEN, CONNECTICUT, A
CORPORATION OF CONNECTICUT.

DESIGN FOR A LEG FOR CHAFING-DISH STANDS.

No. 38,869.

Specification for Design.

Patented Nov. 5, 1907.

Application filed August 13, 1907. Serial No. 388,424. Term of patent 7 years.

To all whom it may concern:

Be it known that I, EDWARD A. GUTERMANN, a citizen of the United States, residing at Meriden, county of New Haven, State of Connecticut, have invented a new, original, and ornamental Design for a Leg for a Chafing-Dish Stand, of which the following is a full, clear, and exact description.

My invention relates to a new, original and ornamental design for a leg for a chafing dish stand.

In the accompanying drawings I have shown the leg in perspective.

I claim:

The ornamental design for a leg for a chafing dish stand as shown.

EDWARD A. GUTERMANN.
